(57) **CLAIM**

The ornamental design for a pump actuator anti-rotation device, as shown and described.

DESCRIPTION

FIG. 1 is a front view of a pump actuator anti-rotation device in accordance with the present teachings.

FIG. 2 is a side view of the pump actuator anti-rotation device of FIG. 1.

FIG. 3 is a back view of the pump actuator anti-rotation device of FIG. 1.

FIG. 4 is a top view of the pump actuator anti-rotation device of FIG. 1.

FIG. 5 is a bottom view of the pump actuator anti-rotation device of FIG. 1.

FIG. 6 is a perspective view of the pump actuator anti-rotation device of FIG. 1.

FIG. 7 is another perspective view of the pump actuator anti-rotation device of FIG. 1.

FIG. 8 is yet another perspective view of the pump actuator anti-rotation device of FIG. 1.

FIG. 9 is an enlarged partial view of the pump actuator anti-rotation device of FIG. 8; and,

FIG. 10 is partial exploded view of the pump actuator anti-rotation device of FIG. 9.

The broken line showing portions of the pump actuator anti-rotation device form no part of the claimed design.

1 Claim, 6 Drawing Sheets
